Geo. McKeith

UNITED STATES PATENT OFFICE.

CHARLES KEMP, OF NEW YORK, N. Y.

LOCK.

1,300,845.

Specification of Letters Patent. Patented Apr. 15, 1919.

Application filed December 9, 1918. Serial No. 265,857.

To all whom it may concern:

Be it known that I, CHARLES KEMP, a citizen of the United States, and a resident of the borough of Manhattan, city, county, and 5 State of New York, have invented certain new and useful Improvements in Locks, of which the following is a specification.

My improvements relate to locks of the character set forth in my concurrent application Serial No. 258,701, filed Oct. 18, 1918, in which a rotatable hasp cylinder is adapted for engagement with the jamb staple or equivalent stationary securing means, the object being to attain a simple but strong 15 and durable burglar proof lock of few parts, in which the operative mechanism is protected and concealed in locked position,—my present invention consisting in the specific construction and arrangement of parts herein- 20 described and claimed.

In the accompanying drawings,

Figure 1, is a vertical sectional elevation taken upon plane of line 1—1, Fig. 2;

Fig. 2, is a horizontal sectional elevation 25 taken upon plane of line 2—2, Fig. 1;

Fig. 3, is a sectional detail taken upon plane of line 3—3, Fig. 1;

Fig. 4, is an elevation in detail of the 30 staple piece;

Fig. 5, is an elevation of what may be designated as the inner or rack side of the bolt;

Fig. 6, is a sectional detail on plane of line 35 6—6, Fig. 2, showing the support for the forward portion of the rack bolt;

Fig. 7, is a sectional elevation taken upon plane of line 7—7, Fig. 1;

Fig. 8, is an elevation of the inner side of the base plate;

Fig. 9, is an edge view of the base plate, 40 showing the connection therewith of the key tumbler member;

Fig. 10, is a front view of a portion of the base plate, showing the key escutcheon etc.;

Fig. 11, is an elevation of the hasp cylinder;

Fig. 12, is an end view thereof;

Fig. 13, is an edge view of the bolt pawl;

Fig. 14, is a partial sectional elevation, 50 similar to Fig. 1, showing the bolt in retracted position.

The casing for the operative parts consists of the base plate B, which is screwed to the door D, or other closure to be protected, and 55 the cover C, which is screwed to the base

plate B, after the latter is secured to the door D. b, b, Fig. 8, represent the holes in the base plate B, for the screws by which said plate is secured to the door D; and b', b', the female threaded posts which receive 60 the screws by which the cover C, is secured to said base plate B.

The cover C, is formed with a semi-cylindrical recess c, for the accommodation of the hasp cylinder H, the ends of which latter are 65 formed each with a radial recess h, (Fig. 12) for engagement with trunnion bosses c, (Fig. 3) on the cover C.

The hasp cylinder H, is essentially hollow in that it is formed with the longitudinal 70 recess h', and lateral slots h², opening thereinto for the accommodation of the arms s, s, and cross bar s', of the staple S, as will be understood by reference more particularly to Figs. 1, 2 and 7, of the drawings. 75

The staple S, is protuberant from an angular base plate S', which is secured to and countersunk in the jamb J, of a door frame or the like as indicated in Figs. 2 and 7,—the lock as before intimated being secured by its 80 base plate B, to the door or other closure D, and it is secured thereto in such manner that the end of the casing in which the hasp cylinder H, is mounted will overlap the staple S, and its plate S', when the door or other 85 closure is turned to closed position. It is to be noted in this connection that edge b', of the base plate B, at this end of the lock terminates short of the edge c'', of this end of the cover C, so as to leave an opening in the 90 lock casing through which the staple S, may project when the hasp cylinder H, is in proper position to receive said staple.

The peripheral surface of the medial portion h³, of the hasp cylinder H, between the 95 opening h', and lateral slots h², h², is formed with gear teeth h⁴, for engagement with rack teeth r, formed for the purpose on the adjacent outer end r', of the rack bolt R. The rear portion of the latter is formed with 100 lateral bearing arms r², r², which rest against the inner side walls of the cover C, as shown particularly in Fig. 1; while the forward medial portion of said rack bolt R, is supported in a recess c², provided for it in a 105 standard c³, forming part of the cover C, as shown more particularly in Fig. 6, the recess being closed by a cap strap c⁴. This method of supporting the rack bolt R, insures the proper alinement thereof, and pre- 110

vents its becoming loose, or falling out of the cover C, when the latter is unattached to the base plate B.

The rear portion of the rack bolt R, is 5 slotted to straddle the cover post c^5 ,—being formed with parallel edges r^3 , r^3 , which contact with said post c^5 , so that the latter also acts as a guide and lateral support for the rack bolt R. The rear of the slot in said 10 rack bolt R, is enlarged to accommodate the bolt actuating cam arms k , l , of the key arbor K, and latch spindle L.

The key arbor K, and the latch spindle L, are positioned in axial alinement, but are not 15 connected with each other in any manner, the latch spindle L, being journaled on the body plate of the cover C, while the key arbor K, is journaled on the base plate B, as shown more particularly in Fig. 2.

20 Pivotaly supported on a trunnion r^4 , on the face of the rack bolt R, next the base plate B, is a spring pawl P, formed with a lateral bearing extension or tongue p' , (shown in Fig. 13) which protrudes through 25 the recess r^5 , formed for it in the rack bolt R, and into the path of action of the afore- said bolt actuating cam arms k , l , of the key arbor K, and latch spindle L. The pawl spring p'' , tends constantly to thrust the 30 pawl P, into the position shown in Fig. 14, with the side walls of its notch p^2 , in engagement with the stationary post c^5 , thereby locking the rack bolt in retracted position and against longitudinal movement in either 35 direction, as shown in Fig. 14. The pawl P, is also formed with a shoulder p^3 , for engagement with said post c^5 , if the pawl is released by the withdrawing of the cam arm k , when the bolt R, is in the forward position 40 as in Fig. 14, thereby locking said bolt against retractile movement until the pawl is again depressed.

When either of the bolt-actuating cam arms k , or l , are turned in the right direction out of normal position, thereby contacting with the bearing tongue p' , of the spring pawl P, the latter is depressed so as to release it from engagement with said fixed post c^5 , (see Fig. 1) freeing the rack bolt 45 R, when the continued movement of the cam arm (k or l) by reason of the engagement of its free end with the side walls of the recess r^5 , throws the rack bolt R, forward, causing it to rotate the hasp cylinder H, and 50 secure the staple S, if in position therefor.

T, represents a key escutcheon and tumbler case of the well known cylinder or pin type, the tongue t , of which engages with the slot k' , in the key arbor K, to actuate the latter 55 in a manner well known in the art.

l^2 , is a spring bearing upon the eccentric portion l^3 , of the latch spindle and tending to hold the spindle as set by means of the latch handle l^3 , also in a manner well known 60 in the art.

As before intimated, although the latch spindle and the key arbor are in axial alinement they are independently rotatable upon their axes. Hence either may be used to reciprocate the rack bolt B, to make or break 70 connection between the hasp cylinder H, and the bolt B, and the staple S.

It will be understood by reference to Figs. 2 and 7, particularly that when the rack bolt R, is shot to locking position the action of 75 the hasp cylinder in engaging the cross bar s' , of the staple is supplemented and reinforced by the outer end of the said bolt itself which also enters the staple, thus effecting a dual locking of the parts that effectually 80 prevents the forcing or "jimmying" of the lock by ordinary known means short of the actual destruction of the lock or the door or other closure sought to be protected. Furthermore all the operative parts of the lock- 85 ing mechanism are inclosed and isolated when connection is made with the staple; and the parts are simple, inexpensive and not liable to derangement under ordinary conditions of use.

90 It will be seen that the distinctive feature of my present invention as compared with my concurrent application for Patent Serial No. 258,701, hereinbefore referred to consists in the combination with the rotatable hasp cylinder H, of the rack bolt R, formed with the slot r , and recess r^5 , and provided with the spring pawl P, formed with the notch p^2 and detent p^3 , in conjunction with the key arbor K, formed with the cam arm k , 95 and the latch spindle L, formed with the cam arm l , for the purpose and operating in the manner set forth.

100 What I claim as my invention and desire to secure by Letters Patent is,—

1. In closure means of the character designated, in combination with a jamb staple or equivalent stationary securing means, a lock comprising a rotatable hasp cylinder adapted to engage with said staple and formed with peripheral teeth, a rack bolt formed with teeth engaging said cylinder teeth, cam arms on the key arbor and latch spindle, a spring pawl pivotally mounted on said rack bolt and formed with a notch for engagement with a stationary part and adapted for engagement with said cam arms on the key arbor and on the latch spindle, together with said key arbor and latch spindles, for the purpose described.

110 2. In closure means of the character designated, in combination with a jamb staple or equivalent stationary securing means, a lock comprising a rotatable hasp cylinder adapted to engage with said staple and formed with peripheral teeth, a rack bolt formed with teeth engaging said cylinder teeth, cam arms on the key arbor and latch spindle, and with a recess adapted to receive 115 and engage with the free ends of cam arms 120

on the key arbor and on the latch spindle, a spring pawl pivotally mounted on said rack bolt and formed with a notch for engagement with a stationary part and also 5 formed with a lateral extension protruding into and through the said recess in the rack bolt, for engagement with the said cam arms on the key arbor and latch spindle, and said key arbor and latch spindle, for the purpose 10 described.

3. In closure means of the character designated, in combination with a jamb staple or equivalent stationary securing means, a lock comprising a rotatable hasp cylinder adapted to engage with said staple and formed with peripheral teeth, a rack bolt formed with teeth engaging said cylinder teeth, cam arms on the key arbor and latch spindle, and with a recess adapted to receive and engage 15 with the free ends of cam arms on the key arbor and on the latch spindle, a spring pawl pivotally mounted on said rack bolt and formed with a notch and a detent shoulder formed for engagement with a stationary part and also formed with a lateral extension protruding into and through the said recess in the rack bolt, for engagement with the said cam arms on the key arbor and latch spindle, and said key arbor and latch spindle, for the purpose 20 described.

4. The combination with a jamb staple or equivalent stationary securing means, of a lock comprising a rotatable hasp cylinder

adapted to embrace and engage with said staple, said cylinder being formed with peripheral teeth, a rack bolt formed with teeth engaging said cylinder teeth and with a recess, a key arbor having a cam arm engageable with said recess, a latch spindle having an arm also engageable in said recess, a 35 spring pawl having a shoulder, means for engagement therewith for withdrawing the cam arm of the key arbor, and means for depressing said pawl to disengage it from said means to free the rack bolt.

5. The combination with a jamb staple or equivalent stationary securing means, of a lock comprising a rotatable hasp cylinder adapted to embrace and engage with said staple, said cylinder being formed with peripheral teeth, a rack bolt formed with teeth engaging said cylinder teeth and with a recess, a key arbor having a cam arm engageable with said recess, a latch spindle having an arm also engageable in said recess, a 40 spring pawl having a shoulder, means for engagement therewith for withdrawing the cam arm of the key arbor, and means for depressing said pawl to disengage it from said means to free the rack bolt.
